UNITED STATES PATENT OFFICE.

BENJAMIN SCHWARTZMAN, OF NEW YORK, N. Y., ASSIGNOR TO SAMUEL SHAPIRO, JOSEPH SHAPIRO, SOLOMON SHAPIRO, DAVE SHAPIRO, AND MORRIS BERMAN, ALL OF NEW YORK, N. Y., COPARTNERS DOING BUSINESS UNDER THE NAME OF RELIANCE METAL SPINNING COMPANY, OF NEW YORK, N. Y.

DESIGN FOR A CANOPY FOR GAS AND ELECTRIC FIXTURES.

49,039.

Specification for Design.

Patented May 9, 1916.

Application filed January 12, 1916. Serial No. 71,790. Term of patent 7 years.

To all whom it may concern:

Be it known that I, BENJAMIN SCHWARTZMAN, a citizen of the United States, residing in the city of New York, borough of Brooklyn, in the county of Kings and State of New York, have invented a new, original, and ornamental Design for a Canopy for Gas and Electric Fixtures, of which the following is a specification, reference being had to the accompanying drawing, forming part thereof.

The figure is a perspective view of a canopy for gas and electric fixtures, showing my new design.

I claim:

The ornamental design for a canopy for gas and electric fixtures, as shown.

BENJAMIN SCHWARTZMAN.
